(57) **CLAIM**

The ornamental design for “magnetic wall-mounted hook,” as shown and described.

DESCRIPTION

FIG. 1 is a front view of the magnetic wall-mounted hook.

FIG. 2 is a back view of the magnetic wall-mounted hook.

FIG. 3 is a bottom-up view of the magnetic wall-mounted hook.

FIG. 4 is a top-down view of the magnetic wall-mounted hook.

FIG. 5 is a right side view of the magnetic wall-mounted hook.

FIG. 6 is a left side view of the magnetic wall-mounted hook.

FIG. 7 is a first perspective view of the magnetic wall-mounted hook; and,

FIG. 8 is a second perspective view of the magnetic wall-mounted hook.

The broken lines in the drawing depict environmental subject matter only and form no part of the claimed design.
